UNITED STATES PATENT OFFICE.

JOHN MASSEY, OF SALEM, MISSOURI.

CIRCLE-IRON FOR WAGONS.

SPECIFICATION forming part of Letters Patent No. 293,840, dated February 12, 1884.

Application filed October 15, 1883. (No model.)

To all whom it may concern:

Be it known that I, JOHN MASSEY, of Salem, in the county of Dent and State of Missouri, have invented a certain new and useful Improvement in Circle-Irons for Wagons, &c., of which the following is a full, clear, and exact description, reference being had to the accompanying drawings, forming part of this specification, and in which—

10 Figure 1 is a top view of the hounds of a wagon having my improved circle-iron secured thereto. Fig. 2 is a side elevation of one of the posts and eyebolts for securing the ends of the circle-iron to the hounds, showing 15 part of the hounds. Fig. 3 is a vertical transverse section taken on line 3 3, Fig. 2; and Fig. 4 is a view of one of the eyebolts removed.

Circle-irons for wagons, &c., have heretofore been made of two pieces of metal welded together at 6, Fig. 1, the two ends being turned down and made fast to the hounds at 7 7 and J J, Fig. 1. It is very inconvenient to weld two pieces of this length together, and the weld is always a weak place in the iron, which 25 is at a point where the greatest strength is required, as the coupling-pole is continually bearing against and wearing it at this point.

My invention consists in making the circle-iron in one continuous piece A, and it is made 30 of wrought iron, and bent as shown in Fig. 1, with separate (or detached) points for fastening the ends of the circle-iron A to the hounds. The inner portion of the circle is secured to the hounds in the usual way, and its outer 35 ends are secured to the hounds by eyebolts C C, in which they are inserted, and which pass down through vertical hollow posts D D, and through the hounds having nuts on their lower ends. The posts have horizontal pro- 40 jections I, that rest upon the hound, and are

secured thereto by bolts J. It will thus be seen that the ends of my improved circle-iron will not have to be bent down and flattened out to rest upon and be secured to the hounds, and the points being made of malleable iron, 45 it is much cheaper than the old style, as above described, which requires a skilled workman to make a neat finish on the ends of the circle. It is compactly drawn to the hounds by the eyebolts, and if it is desired to take it off at 50 any time it can be done by simply loosening the eyebolts. The tops of the hollow posts are preferably notched one way to form beds for the ends of the circle-iron, as shown in Figs. 2 and 3, and the other way to form beds 55 to receive the heads of the bolts. (See same figures.)

I am aware that previous to my invention hollow posts in connection with eyebolts have been used for securing the circle-iron to the 60 hounds at B B; but I do ~~not~~ claim to be the first inventor of such a fastening when applied to the ends of the circle-iron, in combination with a horizontal projection resting upon and secured to the hounds. 65

I claim as my invention—

In combination with a circle-iron for wagons, &c., made of one continuous piece of bent iron, the notched hollow vertical posts with horizontal projections resting upon and secured to the hounds, and the eyebolts in which fit the ends of the circle-iron, and which pass down through the hollow posts and through the hounds with nuts on their lower ends, substantially as and for the purpose set forth. 70

JOHN MASSEY.

In presence of—

J. C. VADEN,
G. M. MANTZ.

Correction in Letters Patent No. 293,340.

It is hereby certified that in Letters Patent No. 293,340, granted February 12, 1884, upon the application of John Massey, of Salem, Missouri, for an improvement in "Circle-Irons for Wagons," an error appears in the printed specification requiring the following correction, viz: The word "not" in line 61 should be omitted; and that the Letters Patent should be read with this correction therein to make it conform to the record of the case in the Patent Office.

Signed, countersigned, and sealed this 18th day of March, A. D. 1884.

[SEAL.]

M. L. JOSLYN,
Acting Secretary of the Interior.

Countersigned:

BENJ. BUTTERWORTH,
Commissioner of Patents.
